UNITED STATES PATENT OFFICE

EDWARD M. SPLAINE, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS

DESIGN FOR A BRIDGE FOR AN OPHTHALMIC MOUNTING

Application filed October 19, 1931. Serial No. 41,426. Term of patent 14 years.

To all whom it may concern:

Be it known that I, EDWARD M. SPLAINE, a citizen of the United States, residing at Southbridge, in the county of Worcester and State of Massachusetts, have invented a new, original, and ornamental Design for a Bridge for an Ophthalmic Mounting, of which the following is a specification, reference being made to the accompanying drawings, forming a part thereof.

Figure I is a front elevation of a bridge for an ophthalmic mounting on an enlarged scale, showing my new design.

Figure II is a plan view of Figure I.

I claim:

The ornamental design for a bridge for an ophthalmic mounting substantially as shown.

In testimony whereof, I affix my signature.

EDWARD M. SPLAINE.
